PRODUCTION OF PARA-XYLENE

John E. Cottle, Bartlesville, Okla., assignor to Phillips Petroleum Company, a corporation of Delaware

Application July 30, 1954, Serial No. 446,772

9 Claims. (Cl. 260—668)

This invention pertains to a process for maximum ultimate recovery of para-xylene from a mixture of xylene isomers and ethyl benzene. More particularly, it pertains to a process wherein a petroleum naphtha hydroformate is separated into a para-xylene product, an ethyl benzene stream and a stream containing a mixture of ortho-xylene and meta-xylene and the subsequent isomerization of these two streams under conditions favorable to the maximum ultimate production of para-xylene.

Para-xylene has for sometime been an article of commerce. The principal sources of para-xylene are now and have been from petroleum and coal tar xylene fractions, which normally consist of ortho-, meta-, and para-xylene and ethyl benzene, the content of the para-xylene varying between 10 and 20 percent. More recently, the development of synthetic fabrics such as "Dacron" has increased the demand for para-xylene to such an extent that the supply of naturally occurring xylenes is insufficient. Thus, considerable interest has been focused upon preferential conversion of other hydrocarbons to para-xylene.

It has been known that the isomeric forms of xylene, namely the ortho-xylene, meta-xylene and para-xylene, can be converted one into the other by isomerization. However, the isomerization has been difficult to accomplish and has taken place at such a slow rate as to make it impractical for commercial operation. Even when the isomerization was carried out under relatively drastic conditions leading to appreciable degradation of the product, the reaction was quite slow. The xylenes have been isomerized by purely thermal means and by treatment under certain conditions with a Friedel-Crafts type catalyst, e.g., aluminum chloride plus hydrogen chloride, but the required conditions were severe, the reaction was slow and the yields were poor.

Further development of the isomerization of xylenes resulted in the use of clay type cracking catalysts. Preferred catalysts of that type have been the acid treated clays or synthetic materials composed largely of silica in combination with alumina and/or magnesia, zirconia, and boric oxide.

It is an object of this invention to provide an improved process for the production of para-xylene. Another object of this invention is to provide a process for the production of increased amounts of para-xylene by the isomerization of ethyl benzene to mixed xylene over a supported platinum or palladium catalyst. A further object is to provide a process for the production of increased amounts of para-xylene by the catalytic isomerization of ortho-xylene and meta-xylene to para-xylene. A more specific object is to provide a process for the production of para-xylene by the separate isomerization of ethyl benzene and a mixture of ortho- and meta-xylene following their separation from a hydroforming process.

The term "reforming" is well known in the petroleum industry and refers to the treatment of gasoline fractions to improve their anti-knock characteristics. Straight run gasolines contain naphthenic hydrocarbons, particularly

of the type having a cyclohexane nucleus, and paraffinic hydrocarbons which usually are of straight chain or slightly branched chain structure, as well as varying proportions of aromatic hydrocarbons. Reforming effects 5 dehydrogenation of the naphthenic hydrocarbons to aromatics, cyclization of the straight chain paraffinic hydrocarbons to aromatics, cracking, and isomerization. The present invention makes use of the dehydrogenation and cyclizing action to convert part of the naphthenic 10 feedstock to xylenes and makes use of the isomerizing action to convert ortho- and meta-xylene to para-xylene. Catalytic reforming processes effected in the presence of hydrogen are known as "hydro-forming" and since the reforming process of this invention employs added hydrogen, it will be referred to as "hydroforming" throughout 15 the subsequent specification and claims.

The present process comprises the steps of hydroforming a petroleum naphtha fraction to produce in part, ethyl benzene and a mixture of xylene isomers, concentrating 20 the aforesaid compounds, dividing the concentrate into three portions, viz. ethyl benzene, para-xylene, and a mixture of ortho- and meta-xylenes, isomerizing the ethyl benzene in a separate unit under such conditions that at least part of the ethyl benzene is converted to xylene 25 isomers, and passing the aforesaid ortho- and meta-xylenes to the feed to the hydroforming zone. The preferred catalyst for the hydroforming step is supported platinum or palladium.

Figure 1 shows a specific embodiment of the invention. 30 A 150°-270° F. petroleum naphtha fraction is fed from line 1 to hydroforming zone 2 along with a mixture of recycled xylenes from 15. The catalyst is a conventional Platforming catalyst of the type described in U.S. 2,479,110. Operating conditions for this zone are 300- 35 550 p.s.i.a., temperature 880° F., LHSV (liquid hourly space velocity) of 2-3, and hydrogen:hydrocarbon ratio about 3½-4% para-xylene, is passed through line 3 along with isomerizate from line 14 to a separation zone indicated generally at 4. 40 This may comprise conventional separation equipment for separating from the xylene-ethyl benzene fraction the products which are lighter and those which are heavier than the fraction. This would normally include fractionators to separate light and heavy materials from the hydroforming effluent, a solvent extraction zone for the separation of paraffins for aromatics, and additional fractionation equipment for the separation of light aromatics from heavy aromatics. This equipment forms no part of the present invention, however, and it is sufficient to indicate that light products are removed at 5 and heavy products at 6. The effluent stream passed through line 7 to crystal purification zone 8 is essentially an equilibrium mixture of the three xylene isomers and ethyl benzene. Zone 8 includes a crystal forming step and crystal 45 purification step, features described in detail in Serial No. 166,992, filed June 9, 1950, now U.S. Patent No. 2,747,001, same assignee. In crystal purification zone 8, the para-xylene is separated from the mixture and withdrawn in essentially pure form at 9. The mother liquor is passed via line 10 to fractionator 11 from which ethyl benzene is taken overhead through line 12 to isomerization zone 13. This is operated at 900° F., a pressure of 365 p.s.i.a., and catalyzed by a platinum catalyst on HF-treated alumina. The isomerizate from 13 is passed 50 through line 14 to line 3 entering the separation zone for reprocessing as described.

The above specific embodiment can be modified as illustrated by Figure 2. This modification parallels that of Figure 1 through the first separation step. Feedstock is fed through line 20 to hydroformer 21 along with recycled mother liquor from line 34 containing mainly

ortho- and meta-xylene. The product passes through line 22, along with isomerize from line 34, to separation zone 23 where light and heavy materials are removed at 24 and 25, respectively, and the xylene-ethyl benzene mixture withdrawn at 26. At this point, unlike the scheme of Figure 1, the mixture enters fractionator 27 where ethyl benzene is removed overhead through line 28 to isomerizer 29, the effluent of which is returned to the system via line 30. The bottoms from fractionator 27, consisting essentially of a mixture of the three xylene isomers, is passed to crystal purification zone 32 through line 31 from which para-xylene is then withdrawn at 33 and the mother liquor recycled through line 34 to hydroformer 2. By operating in this manner considerable reduction in refrigeration cost of the crystallization zone is realized since the ethyl benzene fraction is removed prior to crystallization. The naphtha charge which is hydroformed in the present process is a fraction boiling in the range of 150°-450° F., preferably in the range of 220°-300° F. The preferred catalyst is HF-treated alumina impregnated with between 0.01 and 5 weight percent platinum, preferably 0.1 to 1 weight percent platinum. Another platinum catalyst which may be used is platinum on silica-alumina which preferably has been heat treated to reduce the surface area to within the range of 10 to 70 square meters per gram. These two types of catalyst are described further in U.S. 2,409,109 and U.S. 2,550,531, respectively. As stated before, however, the platinum may be replaced with palladium. The temperature employed in this step is in the range of 700° to 1000° F., preferably 800° to 950° F. A pressure within the range of atmospheric to 1000 p.s.i.g., preferably 200-600 p.s.i.g., is used to obtain the selective formation of xylenes while operating at an LHSV (liquid hourly space velocity) of 0.3-10, preferably 0.5-6. A hydrogen to hydrocarbon mol ratio of between 0.5:1 to 20:1, preferably 1:1 to 10:1, is utilized.

The separation zone following the hydroformer may utilize both fractionation and solvent extraction or may even include extractive distillation and absorption processes in effecting the separation. In a preferred embodiment this separation is operated as follows: a hydrocarbon fraction lower boiling than the xylene, such as the C₅'s and lighter is taken overhead from a fractionator while hydrocarbons higher boiling than the xylenes are removed as kettle product. This leaves a hydrocarbon fraction composed largely of paraffins and aromatics which is then withdrawn as a side stream and solvent extracted to selectively remove the aromatics, leaving the paraffinic hydrocarbons as raffinate. The extract comprising principally ethyl benzene, benzene, toluene, the three xylene isomers, and a small amount of heavy hydrocarbons, is passed to a fractionator along with a mixed xylene isomerize introduced from the ethyl benzene isomerizer. The fractionator separates benzene and toluene as a light fraction, a heavier than xylene fraction as bottoms and a sidestream of xylene concentrate comprising principally the three xylene isomers and ethyl benzene.

The fractionation of the motor liquor (Figure 1) is by conventional means to effect the separation of ethyl benzene from the ortho- and meta-xylenes. The same means are used in the alternative embodiment (Figure 2) wherein this fractionation precedes the para-xylene crystallization step instead of following it. The xylene fraction passed to the isomerization zone from the fractionator undergoes carbon skeleton isomerization in which the ortho- and meta-xylenes are converted in part to para-xylene.

The invention resides primarily in the separation from the xylene concentrate of ethyl benzene and the mixture of ortho- and meta-xylene and the subsequent isomerization of these two streams under conditions favorable to increased production of para-xylene. Ethyl benzene is considerably more difficult to isomerize to para-xylene than is ortho- or meta-xylene. But by separating the

ethyl benzene and isomerizing it separately, conditions can be selected which give an increased conversion of ethyl benzene to isomeric xylenes, including para-xylene.

The catalyst used in the ethyl benzene isomerization 5 step is preferably a supported platinum or palladium catalyst such as that used in the hydroforming zone, although other conventional isomerization catalysts are operative. This reaction is preferably conducted at 10 temperatures of about 900° F. and pressures of 215 to 365 p.s.i.a. An undesirable side reaction of ethyl benzene isomerization is the cracking of the ethyl benzene to benzene and ethane. This reaction does not appear to be 15 affected by pressure but the isomerization of ethyl benzene to para-xylene is favored by higher pressures. Hence, pressures at the upper end of the indicated range should be used since they favor the isomerization of ethyl benzene to para-xylene without at the same time accelerating the undesirable side reaction.

It has previously been proposed to isomerize the crystallizer mother liquor, consisting essentially of ethyl benzene 20 and a mixture of ortho- and meta-xylenes, to produce additional para-xylene. This conversion is based on the fact that the mother liquor contains a lesser amount of para-xylene than that which would be present in an 25 equilibrium mixture of ethyl benzene and ortho- and meta-xylenes. Hence, there is a tendency for the mixture to isomerize in part to para-xylene and thus to approach equilibrium. However, the several components of the mixture do not isomerize to para-xylene at the same rate 30 under the same conditions. Assuming recycling to extinction, and that the components of the mother liquor behave as if they were pure components, the following ultimate yield of figures have been calculated for the components of the mother liquor.

Conversion, Percent	Meta-Xylene	Ortho-Xylene	Ethyl Benzene
P-xylene.....	57.7	53.2	45.2
Light and heavy material.....	42.3	46.8	54.8

From these figures it can be seen that meta-xylene is the component producing the highest yield of para-xylene. The meta-xylene and orthoxylene are converted to para-xylene about 28 and 18 percent, respectively, more efficiently than is ethyl benzene.

When ethyl benzene is isomerized separately, however, it is converted to all three xylene isomers because ethyl benzene is the only component that is present in an 50 amount in excess of equilibrium. Even under ideal conditions, it is not possible to convert much of the ethyl benzene to para-xylene per pass, but a considerable amount is converted to meta-xylene. And, since meta-xylene produces more para-xylene than the other isomers, 55 once the ethyl benzene is converted to meta-xylene it is comparatively easy to re-isomerize the latter to para-xylene.

In the isomerization of the ortho- and meta-isomers in the hydroformer, there is a tendency for some of these 60 isomers to be converted to ethyl benzene; however, by leaving some ethyl benzene in the recycle stream, it is possible to minimize this tendency. In fact, it is difficult to prevent a certain amount of ethyl benzene from being recycled to the hydroformer along with the xylenes.

This case is related to S.N. 347,358, filed April 7, 1953, 65 now U.S. Patent No. 2,741,646, and S.N. 345,167, filed March 27, 1953, same assignee.

I claim:

1. In a process for the production of para-xylene which 70 comprises subjecting to catalytic hydroforming conditions a feedstock containing a mixture of xylene isomers to form as effluent a product containing a mixture of xylene isomers and ethyl benzene, wherein the catalyst employed in hydroforming said feedstock is a supported noble metal 75 selected from the group consisting of platinum and palladium.

ladium, the improvement comprising dividing three portions out of the effluent, namely, para-xylene, ethyl benzene, and a mixture of ortho- and meta-xylene; recycling the latter mixture to the hydroforming zone for partial isomerization to para-xylene, separately and catalytically isomerizing in the presence of said catalyst the ethyl benzene portion to convert it in part to a mixture of xylene isomers, mixing the isomerize with the hydroforming effluent for reprocessing, and recovering the para-xylene as product.

2. Process of claim 1 wherein the para-xylene is removed from the system by crystallization.

3. In a process for the production of para-xylene which comprises catalytically hydroforming a petroleum naphtha, to which has been added a mixture of xylene isomers, in the presence of a supported noble metal catalyst selected from the group consisting of platinum and palladium, at elevated temperature and pressure to secure as effluent a product containing a mixture of xylene isomers and ethyl benzene, concentrating said mixture by separating therefrom the other components of the effluent, and recovering para-xylene from the concentrated mixture, the improvement comprising fractionating the remainder of the mixture to separate the ethyl benzene as overhead and the residual ortho- and meta-xlyenes as bottoms, recycling the latter to the hydroforming zone for partial isomerization to para-xylene, separately and catalytically isomerizing in the presence of said catalyst the ethyl benzene to convert it in part to xylene isomers, and returning the isomerize to the system for separation of the para-xylene therefrom.

4. Process of claim 3 wherein the para-xylene is separated by crystallization.

5. In a process for the production of para-xylene which comprises catalytically hydroforming a petroleum naphtha fraction, admixed with recycled xylene isomers, in the presence of a supported catalyst selected from the group consisting of platinum and palladium on a support selected from the group consisting of HF-treated alumina and heat-treated silica-alumina, and at an elevated temperature and pressure to secure as effluent a product containing a mixture of xylene isomers and ethyl benzene, concentrating said mixture by separating therefrom the other components of the effluent, crystallizing para-xylene therefrom, and leaving as mother liquor a solution containing ortho- and meta-xlyenes and ethyl benzene, the improvement comprising fractionating said mother liquor to separate the ethyl benzene from the ortho- and meta-xlyenes, returning the latter mixture to the hydroforming zone to effect partial conversion to para-xylene therein, catalytically isomerizing in the presence of said catalyst the ethyl benzene to form additional xylene isomers, and recycling the isomerization effluent to the system for recovery of the additional para-xylene.

6. In a process for the production of para-xylene which comprises passing into a hydroforming zone a feedstock consisting essentially of recycled ortho- and meta-xylene and a petroleum naphtha fraction boiling within the range of 150°-450° F., contacting said feedstock with hydrogen and a platinum catalyst supported on HF-treated alumina at a temperature in the range of 700°-1000° F., a pressure within the range of atmospheric to 1000 p.s.i.g., a liquid hourly space velocity of 0.3-10, and a hydrogen:hydrocarbon mol ratio of between 0.5:1 to 20:1, to form a product containing a substantial quantity of xylene isomers and a minor amount of ethyl benzene, removing from the product substantially all products other than said xylene isomers and ethyl benzene, and crystallizing para-xylene from this mixture, the improvement comprising fractionating the residual mother liquor into an ethyl benzene overhead and a bottoms mixture comprising ortho- and meta-xylene, recycling the latter mixture to the hydroforming zone to effect partial conversion therein to para-xylene, isomerizing the ethyl

benzene in the presence of a platinum catalyst supported on HF-treated alumina and at elevated temperature and pressure to form additional para-xylene, and recycling the isomerize to the system for recovery of para-xylene therefrom.

5 7. In a process for the production of para-xylene which comprises catalytically hydroforming petroleum naphtha, admixed with recycled ortho- and meta-xylene, in the presence of a catalyst selected from the group consisting of platinum and palladium on a support selected from the group consisting of HF-treated alumina and heat-treated silica-alumina, at an elevated temperature and pressure to secure as effluent a product containing a mixture of xylene isomers and ethyl benzene, and concentrating said mixture by separating therefrom the other components of the effluent, the improvement comprising fractionating the concentrated mixture to remove ethyl benzene overhead, leaving a mixture consisting essentially of the three xylene isomers, crystallizing para-xylene from the latter mixture, separating mother liquor from the para-xylene crystals, recycling the remaining isomers to the hydroforming zone to form additional para-xylene, isomerizing in the pressure of said catalyst the ethyl benzene in a separate zone, and recycling the isomerization effluent to the first separation step for reprocessing and recovery of the para-xylene.

10 8. In a process for the production of para-xylene which comprises passing into a hydroforming zone a feedstock consisting essentially of recycled ortho- and meta-xylene and a petroleum naphtha fraction boiling within the range of 150°-450° F., contacting said feedstock with hydrogen and a platinum catalyst supported on HF-treated alumina at a temperature in the range of 700°-1000° F., a pressure within the range of atmospheric to 1000 p.s.i.g., a liquid hourly space velocity of 0.3-10, and a hydrogen:hydrocarbon mol ratio of from 0.5:1 to 20:1 to form a product containing a substantial quantity of xylene isomers and a minor amount of ethyl benzene, and removing from the product in a first separation zone substantially all products other than the ethyl benzene-xylene mixture, the improvement comprising fractionating said mixture to separate the ethyl benzene therefrom, leaving as bottoms a mixture comprising the three xylene isomers, crystallizing para-xylene from the bottoms mixture and returning the mother liquor to the hydroforming zone to effect isomerization of the ortho- and meta-xylene content thereof to para-xylene, contacting the ethyl benzene with a catalyst consisting of platinum on HF-treated alumina at an elevated temperature and pressure to effect partial isomerization to xlyenes, and recycling the isomerization effluent to the first separation zone for reprocessing and subsequent recovery of para-xylene.

15 9. Process of claim 8 wherein the isomerization is conducted at a temperature of about 900° F., a pressure of from 215-365 p.s.i.a., and a liquid hourly space velocity of 0.3-10.
